UNITED STATES PATENT OFFICE.

RICHARD GEMMRIG, OF SOUTH PASADENA, CALIFORNIA.

CONCRETE-MIXER.

1,144,650.

Specification of Letters Patent. Patented June 29, 1915.

Application filed October 29, 1913. Serial No. 798,027.

To all whom it may concern:

Be it known that I, RICHARD GEMMRIG, a citizen of the United States, residing at South Pasadena, in the county of Los Angeles, State of California, have invented new and useful Improvements in Concrete-Mixers, of which the following is a specification.

This invention relates to concrete mixers, and the principal object is to provide a concrete mixer of the street paving type with a plurality of conveyors to lift the various materials from the ground level to be delivered into elevated measuring hoppers. It is also an object to provide a concrete mixer with independent chutes to convey the different ingredients that compose the concrete, and operate each individually or cooperatively as desired. It is also an object to provide means for measuring a certain amount of ingredients in an elevated position and under the control of a single operator to be delivered to a common delivery hopper. It is a further object to provide means for folding a portion of the endless conveyors occupying a position next to the ground level, together with a movable measuring box by means of which small quantities can be measured from the elevated hoppers as desired.

In the drawings accompanying this specification, Figure 1 is an elevation showing the application of the invention to an ambulatory concrete mixer. Fig. 2 is a side elevation of a portion of a movable concrete mixer, showing the invention applied thereto. Fig. 3 is a front elevation of the mixer, showing the endless conveyors and the means for driving the same. Fig. 4 is a section on the line 4—4 of Fig. 2 viewed in the direction indicated by the arrows, the section being through the elevated hoppers and the platform adjacent thereto and the driving shaft of the prime mover. Fig. 5 is a perspective view of the elevated measuring hoppers with their discharge gates into the main chute or hopper, together with the auxiliary measuring box. Fig. 6 is a detail

section on the line 6—6 of Fig. 5, viewed in the direction indicated by the arrows, showing an enlarged view of the auxiliary measuring box and its attachments. Fig. 7 is a detail plan view of the drive shaft intermediate of the prime mover and the drive chains for the conveyors, showing the clutch mechanism.

Heretofore in the operation of mixers for paving machines a large skip or hopper has been used into which the ingredients were measured and dumped at the ground level necessitating the presence of a large number of laborers at this point to bring the proper materials for the mixture, together with the delay in delivering the material should one or the other of the ingredients be more remote from the mixer or a mistake be made by the material man and his handlers, and with these large movable skips greater danger is incurred of their falling with the heavy weight and injuring the workmen.

This invention overcomes the above difficulties in that the materials are deposited in rows on the ground level by the dump wagons and shoveled into the lower hoppers without the use of wheel barrows and elevated by conveyors incapable of falling to injure the men seriously, and the control of the mixing operation can be performed by one man who is stationed on a platform adjacent the elevated measuring hoppers, who at all times has complete control over the conveyors and an unobstructed view of all the operations of the machine.

More specifically in the drawings, 7 designates the wheeled frame mounted upon front wheels 8 revolvably mounted upon the axle 9, the wheels being preferably located beyond the side bars of the frame 7 so that a stable base is provided, larger wheels 13 supporting the rear portion of the machine, and which are commonly geared as desired to the prime mover or motor 10 mounted upon the frame so that the machine is self-propelled, the concrete paving being laid as the machine is progressed along the roadway or structure to be supplied with concrete.

The engine 10 has a clutch member 11 se-

cured thereto which is adapted to be thrown into mesh with the member 12 keyed to a shaft 14, this clutch being operated by means of a handle 15 with the yoke connections 16. The connections from this shaft 14 to the movable parts of the invention will be described later.

Secured to the forward end of the frame 7 by means of removable fastenings are a plurality of hinged hoppers 19 preferably formed of the common scoop shape shown, having open tops with curved bottoms, side bars 20 being provided which are hinged by pins 21 to brackets 22 projecting outwardly and upwardly from the end of the frame supporting the plates 18. These plates 18 are preferably securely fastened to the side frame and extend outwardly, and bolts or pins 23 are passed through the straps 18 and suitable apertures in the outer side walls of the two end hoppers 19, the hoppers being preferably joined together by means of plates 24 and 25 so that the whole series may be lifted to clear the ground when it is desired to move the machine any great distance. The bars 20 also form supports for short cross shafts 26 which are transversely disposed in the hoppers 19, these shafts 26 being preferably journaled in boxes 27 which are slidably mounted in frames 28 and regulated by means of an adjusting screw 29 having a locking nut 30 thereon, suitable slots being provided in the side walls of the hoppers to provide for this adjustment or tension of the endless conveyer chains 31 which are carried over the pinions 32 mounted on the shafts 26. Two of these pinions 32 are preferably keyed to each one of the short shafts 26 spacing the parallel disposed chains 31 which are carried upwardly and rearwardly in relation to the machine over pinions 33 mounted on shafts 34, which shafts are journaled in a frame having the bars 36 which are in line with the bars 20 in their normal position so that the chains travel in parallel relation and preferably rearwardly from the hoppers 19. Extending transversely across the chains and supported by suitable means thereon are a plurality of elongated buckets 37, which, with the movement of the chain, pass into close proximity to the rounded bottom wall of the hoppers and as these chains pass over the pinions 33 the buckets dump their contents into the elevated hoppers 38. These hoppers 38 are shown as one continuous bin, having end walls 39 and division walls 40 so that they are divided into the same number of compartments or hoppers 60 as there are elevating conveyers and hoppers 19, and the bottoms thereof are inclined rearwardly or toward the apertured rear wall 41 of the structure, there being an aperture 42 for each bin or hopper closed

by a sliding door 43 vertically slidable in 65 vertically disposed guides 44. Each gate 43 is provided with a handle bar 45 having a hand-hold 46 thereon, these handle bars preferably disposed so that they extend above the top of the rear wall when the 70 gates are closed.

Immediately under the storage hoppers is the delivery hopper 48 having a chute or nose 49 which extends in the usual manner into the mixing drum 50 which is revolved 75 by means of the gearing 51 in the usual manner. Slidably mounted in relation to the openings in the storage hoppers and transversely across the receiving hopper 48 is a measuring box 53 preferably of the rectangular form shown having apertured brackets 54 which engage a rod 55 transversely supported in the hopper 48, the brackets being disposed at the lower inner corner of the box, and for the support for 80 the outer upper corner and to hold the same in the proper position on one of the gates 42, a chain 56 is shown having a hook 57 which hooks over another sliding bar 58 which is supported on brackets 59 which 90 extend from the side walls 39 of the hoppers 38.

To drive the elevating conveyers a gear 60 is keyed to the shaft 14, previously mentioned, which meshes with a gear 61 mounted on a longitudinally disposed short shaft 62 which meshes and turns by means of beveled gears 63 a shaft 64 which is transversely disposed upon the frame 7. This gearing is preferably to one side of the 100 frame and the mixing tube 50, and the oppositely disposed end is provided with a pinion 65 which engages a chain 66 carried over a pinion 67 on a shaft 68 vertically disposed over the shaft 64 and preferably supported just below the platform 69 upon which the conveyer operator stands who controls the measuring of the component elements of the concrete.

This shaft 68 has a plurality of clutches 110 70, 71, 72, and 73, the opposite members of these clutches being formed on the hubs of pinions 74, 75, 76, and 77, respectively, these pinions being freely movable upon the shaft held in proper position by suitable sleeves 115 thereon, each one of these pinions having a chain 78 carried thereon upwardly and over pinions 80 to 84, respectively, which are mounted and keyed on the short shafts 34, there being one of these short shafts for 120 each one of the endless conveyers. To control the operation of these clutches each clutch is provided with a yoked arm 85 pivoted at a point 86 and provided with an operating rod 87 which is connected to the 125 lower end of a lever 88 pivoted in relation to the platform 69, the hand-holds 89 of these levers there being four, placed in line

with one another and so disposed that they are readily handled by the left hand of an operator standing upon the platform 69.

The operation of the invention will be readily understood from the description and drawings; when it is desired to begin mixing concrete, the engine 10 is started and the clutch 11 engaged by means of its operating lever 15 and the operator will then mount to the platform 69 where he can throw either one or all of the conveyer belts into gear and elevate material shoveled from the parallel piles into the hoppers 19 until the required amount is stored in each one of the measuring hoppers and from these hoppers the proper quantity can be dumped, the cement being measured by means of the measuring box 53, the latter being dumped by unhooking the hook 57 and the contents will be capsized and dropped from the chute into the mixing drum. From this point the operator may readily see all the operations of the machine and control same as occasion may require. The one volition required of those who shovel the material into the hoppers 19 is that they shall put the proper ingredients into the same hopper each time, one being provided for the cement, sand, gravel and crushed stone.

As the machine advances upon the wooden platform usually laid for the material and to support the wheels, the lower bar 24 readily slides and when it is desired to move the machine any great distance when not in operation as a mixer, the hoppers 19 with their short shafts and portions of the conveyers may be folded up out of the way as shown in dotted lines in Fig. 2 by removing the bolts or pins 23.

What I claim is:

1. In a paving machine the combination of a wheeled frame, a supporting frame on said wheeled frame, a plurality of hoppers mounted on said supporting frame having openings in their dependent portions, gates adapted to control the exit of material from said openings, a delivery hopper adjacent said elevated hoppers, a plurality of hoppers adjacent the ground, means to afford communication from said lower hoppers to said elevated hoppers, and a measuring box supported intermediate the openings in said elevated hopper, and said delivery hopper, whereby the material delivered to said delivery hopper may be measured.

2. In a paving machine the combination with a wheeled platform and a motor thereon, of a pair of series of hoppers, one series of said hoppers being secured adjacent the ground on said platform and the co-operating series of said hoppers elevated above said platform, a conveyer supporting frame extending into the lower of said hoppers and adjacent said upper hopper, endless convey-

ers supported on said conveyer frame and 65 adapted to carry material from the lower of said series to the upper of said series of compartments, short shafts mounted in said frame to support the ends of each of said endless conveyers, pinions keyed to said 70 shaft, a driving shaft, pinions mounted on said shaft, chains connecting said pinions to one of said short shafts connected to each of said endless conveyers, and means to connect said pinions on said driving shaft with 75 said motor collectively or individually as desired.

3. In a paving machine, a wheeled frame, a supporting frame thereon, a hopper on said supporting frame, means for controlling the delivery of materials from said hopper, a delivery hopper adjacent said elevated hopper, a measuring box adapted to receive materials delivered from the elevated hopper and to discharge same into the delivery hopper, a hopper arranged adjacent the ground, and means for conveying materials from said last-named hopper to the elevated hopper.

4. In a paving machine, a delivery hopper, 90 an elevated hopper having a discharge opening leading to the delivery hopper, a gate controlling the discharge opening of the elevated hopper, a measuring box arranged beneath the discharge opening of the elevated 95 hopper, a pivotal mounting for said measuring box, and means for holding said measuring box against movement.

5. In a paving machine, a delivery hopper, a plurality of elevated hoppers having discharge openings communicating with the delivery hopper, gates controlling the exit of material from said discharge openings, a measuring box adapted to be positioned to receive the materials discharged from any 105 one of the elevated hoppers, a pivotal support for said measuring box, and means for holding the measuring box against movement.

6. In a paving machine, a delivery hopper, 110 a plurality of elevated hoppers having discharge openings communicating with the delivery hopper, gates controlling the exit of materials through said discharge openings, a rod extending horizontally below said discharge openings, a measuring box pivotally and slidably mounted on said rod adapted to be disposed beneath the discharge opening of any one of said elevated hoppers, and means for holding the measuring box against 115 movement.

7. In a paving machine, a delivery hopper, a plurality of elevated hoppers having discharge openings communicating with the delivery hopper, gates controlling the exit of 125 materials through said discharge openings, a rod extending horizontally below said discharge openings, a measuring box pivotally

and slidably mounted on said rod adapted to be disposed beneath the discharge opening of any one of said elevated hoppers, means for holding the measuring box against movement, a plurality of receiving hoppers disposed adjacent the ground, and means for delivering materials from said receiving hoppers to the elevated hoppers.

In witness that I claim the foregoing I have hereunto subscribed my name this 13th ¹⁰ day of October, 1913.

RICHARD GEMMRIG.
